Fig. 1.

MERCHANDISE VENDER CARD

THE CONVENIENCE VENDER CARD
THERE ARE 12 NUMBERS ON EACH TICKET RANGING FROM 1 TO 12

-DIRECTIONS FOR PLAYING-

WRITING YOUR NUMBER OR NUMBERS IN BLANK SPACE UNDER TICKET YOU INTEND TO PULL. IF YOU PLAY 3 NUMBERS FOR 5¢ AND THEY ARE IN THE DRAWN TICKET YOU GET 50¢ PRIZE. YOU CAN PAY ANY AMOUNT FOR TICKET BEFORE PULLING THE TICKET OFF THE CARD. YOU WILL GET 10¢ PRIZE PROPORTIONALLY TO AMOUNT PAID FOR TICKET. IF ALL NUMBERS OR NUMBERS PLAYED ARE ON THE TICKET PULLED, YOU WILL GET 10¢ PRIZE.

CLASS NO. A.1.

UNITED STATES PATENT OFFICE.

JULIUS D. HIRSCH, OF SAVANNAH, GEORGIA.

GAME APPARATUS.

1,028,724.

Specification of Letters Patent. Patented June 4, 1912.

Application filed November 20, 1911. Serial No. 661,200.

To all whom it may concern:

Be it known that I, JULIUS D. HIRSCH, a citizen of the United States, and a resident of Savannah, in the county of Chat-
5 haun and State of Georgia, have invented certain new and useful Improvements in Game Apparatus, of which the following is a specification.

This invention is an improvement in game 10 apparatus and has for an object to provide a game wherein the element of chance will be largely involved and in which will be provided means whereby the player may indicate a number or series of numbers which 15 he selects as probably occurring upon the series of number of a particular ticket; and the invention consists in certain novel constructions and combinations of parts as will be hereinafter described and claimed.

20 In the drawing Figure 1 is a face view of an apparatus embodying my invention. Fig. 2 illustrates in detail one of the tickets in which the body portion of the ticket and the numbered slip are made separate and 25 pasted together. Fig. 3 illustrates a ticket in which the body portion and the numbered slip are integral.

By my invention, I provide an apparatus comprising a table whereon are provided, 30 what for convenience of reference, I term ticket spaces and indicating spaces adjacent to and corresponding with their respective ticket spaces. In connection with the table I employ tickets, one for each ticket space 25 and these tickets are adhesively attached over the respective ticket spaces and have each an under folded numbered slip containing a series of numbers. These tickets are designated, preferably by numbers, cor- 40 respondingly with their respective ticket spaces and I also correspondingly designate the ticket spaces and their respective indicating spaces. The tickets are provided with numbers, twelve to each ticket, the numbers

45 ranging from 1 to 78 in the particular illustration shown, and the series of 12 numbers on any one ticket are not duplicated on any other ticket. I do not mean by this the number 1 or the number 78 or any intermediate number does not appear on any two tickets, but I mean to be understood that the particular combination of figures appearing on any one ticket is not duplicated on any other ticket, the series being worked 50 out by combinations in order to avoid duplications of series.

In the construction shown, the table A has the ticket spaces B and the indicating spaces C adjacent thereto and the corresponding ticket spaces and indicating spaces bear the 60 same number, this being the preferable designation. Thus the first ticket space may be numbered 1 and the indicating space immediately below said ticket space numbered 1 will also be numbered 1 and the ticket D 65 applied to the space 1 will also be numbered 1 so that the ticket space, its respective indicating space and the ticket for application to the said ticket space will all bear the same designation, this, for convenience, 70 being preferably a number as shown. The second ticket space and its respective indicating space and the ticket for application to said second ticket space will be numbered 2 and so on throughout the series of 75 ticket spaces and corresponding designating spaces of which any suitable number may be provided on the table. I have shown the table as provided with 120 ticket spaces, but manifestly this may be varied as desired. 80

The tickets D may be made with a body portion D' and a numbered slip D² pasted or otherwise secured thereto as shown in Fig. 2 and this may be preferred for convenience or it may be desired in some instances to cut the body portion D' and the numbered slip D² in one piece as shown in Fig. 3 of the drawing.

As shown and preferred, a series of 12 numbers is provided on each ticket slip and this ticket slip is folded under when the ticket is applied to its space B, the ends or wings of the body portion D' projecting laterally so that they may be adhesively secured to the table A in such manner as to 90 hold the folded ticket slip flat against the table so its numbers cannot be inspected until the ticket is torn from the table by the player who selects such particular ticket in playing the game. 95

In practice, the player may choose 1, 2, 3 or more numbers, his guess being that the number or series of numbers which he chooses will be found among the series of numbers on the ticket which he may select. 100 When he has chosen his series of numbers and has selected his ticket, he must write the series of numbers he chooses in the space C immediately below the ticket which he has selected. This is done to avoid any discussion or disagreement as to the numbers which he may choose or the particular ticket 110

which he may select. After choosing his numbers and selecting his ticket and writing his chosen numbers in the proper space immediately below his selected ticket, the 5 player may tear the ticket from the table and open the numbered slip and determine whether the particular number or series of numbers he has chosen appears in the list of numbers on his selected ticket. If so, he 10 is entitled to the prize which may be agreed upon in any particular instance. In the particular illustration shown, the player may buy a ticket for five cents and may then elect to choose one number or two numbers or 15 three numbers or other numbers upon a particular ticket. If he chooses three numbers and these numbers appear on the ticket he selects, he will be entitled to five dollars' worth of merchandise without further payment. If he chooses two numbers and these 20 two numbers appear on the ticket he selects, he will be entitled to seventy-five cents' worth of merchandise without further payment and if he chooses a single number and it is on the ticket he selects, he will be 25 entitled to 15 cents' worth of merchandise without further charge. Manifestly the game may be played for other prizes and various combinations may be played as desired. Thus it may be decided for the player 30 to choose four numbers and then if any three of these numbers or all of these numbers appear on the ticket he selects, he will be entitled to a prize or prizes as agreed. Of course, with such a combination, the player 35 should be required to pay a greater sum or penalty as his chance of winning is increased accordingly. It will be understood that various other combinations and ways of 40 playing the particular game above described, may be devised and other games may be played with the apparatus without involving a departure from the broad principles of my invention.

45 To prevent a player from taking a ticket previously used on one table and by sleight of hand or other trick substituting it for a ticket which he may take off the table being played, I prefer to distinguish or identify 50 the tickets applied to any particular table

with such table and this may be done by means of a class designation, such as "Class A'" shown at E on the table and "Class A'" shown at E' on the ticket so that each ticket will be identified with the particular table 55 to which it is connected in the first instance.

I claim:

1. A game apparatus, substantially as herein described, comprising a table having ticket spaces and indicating spaces adjacent to and corresponding with their respective ticket spaces, tickets detachably attached to their respective ticket spaces and having under folded numbered slips containing a series of numbers, the said tickets and the 60 indicating spaces corresponding to the ticket spaces of said tickets being correspondingly designated, substantially as and for the purposes set forth.

2. A game apparatus comprising a table 70 having spaces and a series of tickets detachably secured to the table and corresponding to their respective indicating spaces of the table, the said spaces and tickets being correspondingly designated.

3. A game apparatus comprising a table having designated spaces adapted to receive numbers chosen by a player, and tickets detachably connected with the table and corresponding to said designated spaces and 80 suitably designated whereby they may be identified with their respective spaces, said tickets having series of numbers concealed when the ticket is in connection with the table.

4. In a game apparatus, a table having ticket spaces adapted to receive a ticket, spaces for designations adjacent to their respective ticket spaces and tickets detachably applied to their respective ticket spaces, the 90 tickets and their respective designation space being correspondingly designated.

5. In a game apparatus, a ticket having lateral wings and a numbered slip foldable between said wings.

JULIUS D. HIRSCH.
